UNITED STATES PATENT OFFICE.

HENRY W. FALSTROM, OF BLOOMFIELD, NEW JERSEY, ASSIGNOR TO EASTERN TOOL & MFG. COMPANY, OF BLOOMFIELD, NEW JERSEY.

CLIP FOR ELECTRIC-LIGHT BULBS.

Application filed April 6, 1927. Serial No. 181,347.

This invention relates to an improved means for securing a globe to an electric light bulb, said means consisting of a spring clip, usually of flat spring metal, which clip 5 is secured to the globe at its rim. The clips are arranged in proper number usually three or four and are attached to the globe by simply slipping them on when the globe is handled the clips are really part of it and 10 when the globe is attached or detached the clips remain with the globe.

The globes are cup-shaped and are colored and are placed over bulbs for display purposes on signs and in store windows. They 15 are usually of glass and are held by the clips on the bulbs and cover the ends of the bulbs and extend down over the major portion of the bulb. The clips I have devised will secure the globe to a bulb of the pear-shaped kind or one of the spherical type and 20 on various sizes within reasonable limitations.

The invention is illustrated in the accompanying drawings, in which Figure 1 is a side view of a globe secured to a bulb by 25 my improved form of clip. Figure 2 is a section of the rim of the globe with a clip attached thereto. Figure 3 is a perspective view of a clip.

The globes are cup-shaped and are in general use at present, some being held in place by wire and others being screw-threaded at the rim to fit into sockets. All of these various kinds can be secured by my form of 35 clip.

The drawing shows a bulb 10 with the globe 11 placed over it and supported by it. The clips 12 are secured to the globe by having spring hook-like parts 13 which fit 40 over the rim 14 of the globe.

The hook is usually contracted at the point

15 as compared with the end 16 and the end 17 is inclined outwardly to provide a wider mouth so that the clip can be easily slid on. The constricted part of the hook 45 resists removal so that the clip clings to the globe under normal placement or removal of the globe on or from a bulb.

The part 18 is slightly bulged to the side opposite that of the hook and the end 19 is 50 curled slightly so that it rides easily on the inside face of the globe.

When not on a bulb the clips are under no or little tension, the ends 19 bearing lightly or being free of the inside of the globe. When 55 placed on a bulb, however, the parts 18 of the clips are flattened out and then are under sufficient tension to grasp the bulb and thus support the globe on the bulb.

The globes are secured or removed by 60 simply sliding them in or out of place on the bulb.

I claim:

1. The combination of a cup-shaped globe and an electric light bulb, with a clip having one end to hook over the rim of the globe and with the major portion thereof within the globe and disposed so that it is pressed against the inside of the globe and under a tension when placed over the bulb whereby 65 the globe is detachably secured to the bulb.

2. The combination of a cup-shaped globe and an electric light bulb with clips of spring metal, each clip bent at one end into a hook to engage the rim of the globe and formed 75 for the remainder of its length into a bulged part to engage the globe at the other end of the clip and to engage the bulb between the ends of the clip whereby the globe is supported on the bulb solely by the clips. 80

In testimony whereof I affix my signature.

HENRY W. FALSTROM.
